SANDING DEVICE

Carl Rogers, Port Sandfield, Ontario, Canada

Application April 14, 1948, Serial No. 20,862
In Canada July 30, 1947

8 Claims. (Cl. 51—187)

1

This invention relates to a device for sanding and smoothing down or restoring, by sandpapering or the like, various surfaces to be finished or refinished. More particularly, it relates to a device of the character indicated which may be used in the same manner as a conventional paint brush.

Heretofore it has been the general practice in finishing surfaces, such as those of walls, ceilings, floors, woodwork, furniture and the like, to employ a block or similar device to, or around, which is applied a strip of sandpaper or similar sanding means. This is pressed by the exertion of the operator, with substantial force against the surface to be finished and is moved back and forth while in forceable engagement with the surface. The operator has tired quickly in the use of such blocks or devices because of the pressure he must exert and because the operation must be performed largely with one hand. A right handed worker finds it awkward to operate a block with the left hand and a left handed worker finds it awkward to use the block in the right hand. Moreover, in sanding overhead surfaces, such as ceilings, the necessity of exerting pressure requires the use of the block directly over the head of the worker so that the fine particles of dust created by the operation fall upon the worker and cause considerable discomfort. Furthermore, in the use of a block there is substantial wastage of sandpaper since the latter must be curled or folded around the ends of the block and, therefore, a substantial section at each end of the paper cannot be used.

An object of the present invention has been to provide a sanding device which requires less exertion by the worker in sanding a surface and one which may, therefore, be used more continuously without unduly tiring the worker. Toward this end the device is of such character that it may be employed with a long sweeping stroke, similar to that used in painting, in lieu of the short rubbing strokes employed in the use of a block. Moreover, because of the nature of the device and its mode of use it may be readily manipulated by either hand of the worker. This permits shifting from one hand to the other as one arm of the worker becomes tired.

Another object of the invention has been to provide a sanding device which may be operated

effectively, manually, in such a way that the particles removed through the use of the device will not fall upon the operator.

A further object has been to provide a sanding device which will enable the efficient and substantially full use of the sandpaper, or other expendable sanding means, utilized in its operation.

A still further object has been to provide an inexpensive device of the character indicated which will permit the sandpaper or other sanding means to be readily and quickly changed to vary its texture or coarseness or to replace or reverse it.

Other objects, features and advantages of the invention will appear from the following detailed description of a preferred form of the same which will now be given in conjunction with the accompanying drawings, in which:

Fig. 1 is a face view of an illustrative form of the improved sanding device fully assembled;

Fig. 2 is a side view of the device shown in Fig. 1;

Fig. 3 is a face view of the main body of the device including a handle, a ferrule, and a flexible body member formed into a unitary assembly;

Fig. 4 is a face view of one of the clamping bars or plates for the removable and replaceable sanding material;

Fig. 5 is a cross-section through the plate of Fig. 4, taken along the line 5—5 of Fig. 4;

Fig. 6 is a face view of the plate or bar provided on the opposite face of the main body of the device; and

Fig. 7 is a detail view showing a bolt and wing nut used in association with the plates of Figs. 4 and 6 to releasably clamp the sanding material to the main body of the device.

Referring now to the drawings, the illustrative device comprises a handle 10 having a gripping portion 11 similar to that provided on a conventional paint brush. At the base of the gripping portion the handle has an enlarged shoulder portion 12, this being inserted in and retained by a ferrule 13. Any suitable means, such as nails 14, may be employed for securing the handle and ferrule together. From the opposite end of the ferrule there projects a flexible body member 15 which extends into the ferrule a suitable distance and is retained therein in any suitable way, as by frictional engagement with the inner surface

thereof, and by means of nails 16. The ferrule is preferably provided with circumferential beads near their upper and lower edges for stiffening purposes, although these may be omitted if the material of which the ferrule is formed is sufficiently stiff. The member 15 is preferably formed of rubber, either natural or synthetic, of relatively light weight and porous construction, such as sponge rubber. It may, however, be formed of other suitable materials such as thermoplastic substances and the like having suitable flexibility and resilience or elasticity. It may be formed, for example, of nylon or of a copolymer of vinyl acetate and vinyl chloride which is sold under the tradename "Vynilite". In general, it is important that it should yield and flex in substantially the same manner as the bristle body of a paint brush and it should normally tend to return to the position indicated in the drawings after flexure in either direction. To facilitate the desired bending of the body 15 in response to the use of the device with a long sweeping stroke, similar to that given to a paint brush, it is preferably provided with a long longitudinal slit 17 which extends from its outer end to a point adjacent the ferrule. If desired, a series of such slits may be provided or the body may be formed of a plurality of separate strands or sections of rubber or other suitable material appropriately shaped into a body similar to the bristle body of a paint brush. The opposite faces of the flexible body 15 are preferably substantially flat and arranged to taper inwardly or converge from the edges of the ferrule toward the outer free end of the body. It is important that the member, or members, 15 have substantially the same feel as the bristle body of a paint brush as the device is manipulated across the surface to be sanded with the long sweeping strokes usually given to a paint brush, although it may be somewhat stiffer.

In forming the assembly thus far explained, the ferrule may, if desired, be folded around the base portion 12 of the handle and around the upper end of the flexible body 15 and overlapped at the side of the assembly to form a seam 18. By forming the assembly in this way the flexible member, or members, may be squeezed and held firmly by the frictional action of the ferrule, as well as by the nails 16 and by a nail 19 which may be provided along the edge of the ferrule. If desired, the overlapped portions of the ferrule may be soldered or brazed or otherwise bonded together, or the free ends may be secured by appropriate interlocking and folding or crimping.

A pair of apertures 20 is preferably provided, in suitably spaced relation, through the base of the handle 10 and through the walls of the ferrule. These apertures are adapted to receive the reduced shanks of bolts 21 of the type illustrated in Fig. 7. The reduced cylindrical shanks 22 of these bolts are adapted to slide freely through the apertures 20. At the opposite faces of the device clamping bars or plates 23 and 24 are provided, these being releasably retained by the bolts 21. The plates may extend for the full width of the ferrule but preferably terminate inwardly of the edges, as shown. Plate 23 is formed with a pair of square openings 25 adapted to receive square shoulder portions 26 adjacent enlarged heads 27 of the bolts 21, thus preventing rotation of the bolts in relation to the plate. Plate 24 is provided with circular openings 28 through which the shanks 22 of the bolts may pass freely. Readily releasable means, such as wing nuts 29, are provided at the outer ends of 75

the bolts for clamping the plates secured against the opposite faces of the ferrule and handle.

Plate 24 has an inwardly turned flange or rib 20 along its lower edge and may also be provided with a similar flange or rib 31 along its upper curved edge. Similarly, the plate 23 may be provided with a flange or rib 32 along its lower edge and a flange or rib 33 along its upper curved edge. The flanges 31 and 33 may be eliminated, if desired, and the plates simply bent inwardly slightly at their upper portions to engage the ferrule or the base 12 of the handle to an extent sufficient to maintain the main body of each plate substantially parallel with the face of the ferrule. In this event the central portion of the upper edge of each plate should be straight-lined, instead of curved, to provide for line contact with the handle. If the flanges 31 and 33 are provided, they are preferably interrupted in the region of the upper bead of the ferrule so as to avoid engagement with the latter.

Referring now to Fig. 1, the plates 23 and 24 are adapted to clamp the upper ends of sanding elements 34 which may be in the form of sandpaper, emery cloth, or the like. It should be sufficiently stiff and resilient to return, after flexing, to the position indicated in Fig. 2, but it should flex readily in the use of the device. A sheet of such material is provided along each face of the flexible body 15 of the device, the upper ends 35 of these sheets being clamped against the ferrule by means of the ribs or flanges 30 and 32. If the clamping plates are provided with the flanges 31 and 33 along the entire top and side edges, the upper bead on the ferrule must project outwardly to an extent less than the thickness of the sanding material. At its lower end each sheet may be arranged to terminate substantially flush with the free end of the body 15 or may extend slightly below this. In order to increase the flexibility and effectiveness of the outer end of each of the sheets 34, a series of slits 36 is preferably provided, these extending longitudinally of the sheet for a distance of about $\frac{1}{2}$ ". In order that the sheets may be reversed so that both ends may be subjected to wear before they are discarded, the slits 36 may suitably be provided at both ends. They may, however, be omitted altogether if desired, particularly if the sanding material is sufficiently flexible without the slits.

In the use of the device sandpaper or the like of the desired fineness or coarseness, may be assembled with the main body structure, in the manner indicated in Figs. 1 and 2, and the wing nuts 29 turned sufficiently tightly to firmly clamp the sandpaper against the ferrule. The upper edges of the strips of sandpaper may suitably abut against the upper bead of the ferrule. The device may then be used with a long sweeping stroke similar to that given to a paint brush so that the two faces of the device become alternately effective in sanding the surface to be finished. It will be found that with a given amount of effort and within a specified time a larger surface may be sanded through the use of the improved device than through the use of the conventional sanding block. The worker becomes less tired due to the fact that the device may be used with substantially the same efficiency in either hand. It may, therefore, be shifted from one hand to the other in the course of sanding surfaces.

After the lower half of the sandpaper, or the like, has become worn to the extent that it can

no longer be used efficiently, the clamping means may be loosened and the two sheets of sandpaper may be reversed so that what previously constituted the upper portions may now become the operative lower portions. Substantially the entire surface of the sandpaper may be utilized in this way. So also, if it is desired to start with relatively coarse sandpaper and finish with a finer grade of sandpaper it is a simple matter to replace the sanding strips or sheets at the two faces of the device by the type desired.

While a preferred form of the invention has been disclosed in considerable detail, it will be understood that numerous variations may be made in the construction and arrangement of the several parts without departing from the general principles and scope of the invention. For example, the gripping edges of the plates 23 and 24 may be serrated, or otherwise formed, to grip the sanding strips or sheets more firmly, if desired. Other modifications will suggest themselves to those skilled in the art.

I claim:

1. A manually operable sanding device for use in finishing surfaces which comprises a handle having a hand gripping portion and a base portion, a flexible and resilient body having one end secured to said base portion and its main part projecting therefrom, flexible abrasive strips overlying the opposite faces of said flexible body, and securing devices for retaining said abrasive strips in juxtaposition to the faces of said flexible body, said flexible body and said abrasive strips being adapted to flex freely first in one direction and then the other in substantially the same manner as the bristle body of a paint brush as the outer ends thereof are drawn back and forth across a surface to be finished in a sweeping movement.

2. A manually operable sanding device for use in finishing surfaces which comprises a handle having a hand gripping portion and a base portion, a flexible body formed of rubber-like material having one end secured to said base portion and its main part projecting therefrom, flexible abrasive strips overlying the opposite faces of said flexible body and securing devices for retaining said abrasive strips in juxtaposition to the faces of said flexible body, said flexible body and said abrasive strips being adapted to flex freely first in one direction and then the other in substantially the same manner as the bristle body of a paint brush as the outer ends thereof are drawn back and forth across a surface to be finished in a sweeping movement.

3. A manually operable sanding device for use in finishing surfaces which comprises a handle having a gripping portion and a base portion, a flexible and resilient body having one end secured to said base portion and its main part projecting therefrom, said flexible body having dimensions comparable with those of the bristle body of a chisel-pointed paint brush, flexible abrasive strips overlying the opposite faces of said flexible body and securing devices for retaining said abrasive strips in juxtaposition to the faces of said flexible body, said flexible body and said abrasive strips being adapted to flex freely first in one direction and then the other in substantially the same manner as the bristle body of a paint brush as the outer ends thereof are drawn back and forth across a surface to be finished in a sweeping movement.

4. A manually operable sanding device for use in finishing surfaces which comprises a handle

having a hand gripping portion and a base portion, a flexible body having one end secured to said base portion and its main part projecting therefrom, said flexible body being formed of soft resilient material and having substantially flat outer faces, said body tapering inwardly from a relatively thick portion adjacent the handle to a relatively thin portion at the free outer end, flexible abrasive strips overlying the opposite faces of said flexible body, and securing devices for retaining said abrasive strips in juxtaposition to the faces of said flexible body, said flexible body and said abrasive strips being adapted to flex freely first in one direction and then the other in substantially the same manner as the bristle body of a paint brush as the outer ends thereof are drawn back and forth across a surface to be finished in a sweeping movement.

5. A manually operable sanding device for use in finishing surfaces which comprises a handle having a hand gripping portion and a base portion, an integral flexible body having one end secured to said base portion and its main part projecting therefrom, said flexible body being formed of resilient material and adapted to yield under pressure and being divided longitudinally to facilitate flexing, flexible abrasive strips overlying the opposite faces of said flexible body, and securing devices for retaining said abrasive strips in juxtaposition to the faces of said flexible body, said flexible body and said abrasive strips being adapted to flex freely first in one direction and then the other in substantially the same manner as the bristle body of a paint brush as the outer ends thereof are drawn back and forth across a surface to be finished in a sweeping movement.

6. A manually operable sanding device for use in finishing surfaces which comprises a handle having a hand gripping portion and a base portion, a ferrule surrounding said base portion and secured thereto, an integral flexible body formed of resilient, yieldable material having one end retained by said ferrule and having its main portion projecting therefrom, releasable clamping means mounted on said ferrule, and flexible abrasive sheets overlying the opposite faces of said flexible body and having one of their ends retained by said clamping means, said flexible body and said abrasive sheets being adapted to flex freely like the bristle body of a paint brush as the outer ends thereof are swept back and forth across a surface to be finished.

7. A manually operable sanding device for use in finishing surfaces which comprises a handle having a hand gripping portion and a base portion, a ferrule surrounding said base portion and secured thereto, a solid flexible, resilient, yieldable body having one end retained by said ferrule and having its main portion projecting therefrom, said body being divided in the direction of its length from the outer end thereof to a point adjacent the ferrule, a releasable clamping means mounted on said ferrule, and flexible abrasive sheets overlying the opposite faces of said flexible body and having one of their ends retained by said clamping means, said flexible body and said abrasive sheets being adapted to flex freely like the bristle body of a paint brush as the outer ends thereof are swept back and forth across a surface to be finished.

8. A manually operable sanding device for use in finishing surfaces which comprises a handle having a hand gripping portion and a base portion, a ferrule surrounding said base portion and

secured thereto, a flexible body formed of resilient, yieldable material having one end retained by said ferrule and having its main portion projecting therefrom, releasable clamping means mounted on said ferrule, said clamping means comprising bars with gripping edges extending transversely across said ferrule at the opposite faces thereof and means for releasably retaining said bars, and flexible abrasive sheets overlying the opposite faces of said flexible body and having one of their ends retained by said gripping edges of said clamping means, said flexible body and said abrasive sheets being adapted to flex freely like the bristle body of a paint brush as

the outer ends thereof are swept back and forth across a surface to be finished.
